UNITED STATES PATENT OFFICE.

ALVAH A. HOFFMAN, OF PLEASANTVILLE, PENNSYLVANIA.

PORCH-SWING.

SPECIFICATION forming part of Letters Patent No. 735,378, dated August 4, 1903.

Application filed May 19, 1903. Serial No. 157,881. (No model.)

To all whom it may concern:

Be it known that I, ALVAH A. HOFFMAN, a citizen of the United States, residing at Pleasantville, in the county of Venango and State 5 of Pennsylvania, have invented a new and useful Porch-Swing; and I do hereby declare the following to be a full, clear, and exact description of the invention, such as will enable others skilled in the art to which it appertains to make and use the same.

The invention relates to a porch-swing, and has for its object to improve the construction of swings and to provide a simple, inexpensive, and efficient one designed particularly 15 for use on porches and similar places and adapted to be readily operated by either an adult or child.

A further object of the invention is to provide a swing of this character of great strength 20 and durability, in which there will be nothing to get out of order and which will not be liable to catch or injure a child.

With these and other objects in view the invention consists of the construction and 25 novel arrangement of parts hereinafter described and shown, and particularly pointed out in the claims hereto appended.

In the drawings forming part of this specification, and in which like numerals of reference designate corresponding parts, Figure 1 is a perspective view of a swing constructed 30 in accordance with this invention. Fig. 2 is a detail view illustrating the manner of mounting the actuating-lever.

Referring to the drawings, 1 designates a chair, which may be constructed of any desired size and of any suitable material and which is preferably provided with central and side pieces 2 and 3, each constructed of a single piece of material, as shown. The central and side pieces 2 and 3 are connected by transverse slats 4, and the chair is provided at opposite sides with arms 5, connected at their rear ends with the back of the chair and 45 supported at their front portions by upright pieces 6, secured to the front portion of the chair at opposite sides thereof; but the arms may be mounted in any other desired manner, and the foot portion 7 of the chair is supported by braces 8. The braces 8 extend from the foot portion to the front ends of the arms. The chair is suspended from the top

of the porch or other suitable support by suspension-ropes 9, secured at their lower ends to ears 10 of attachment-plates 11 by snap-hooks 55 12; but any other form of suspension device, such as a rod or bar, may be employed, as will be readily understood. The attachment-plates are secured to the end of the arms, and the ears consist of upright portions extending 60 from the plates at right angles to the same. One of the rear ropes is engaged by an actuating-lever 13, fulcrumed by a rivet 14 or other suitable fastening device on the back of the chair near its upper end and having its upper 65 end 15 bent outward and extended to a point in advance of the rear suspension-rope, as clearly shown in Fig. 1. The lower arm of the lever extends downward through a horizontal guide 16 and depends below the seat 70 of the chair, to which the guide is secured. The guide is secured to the seat at one side thereof and it extends rearward therefrom and it is adapted to maintain the lever plumb to prevent the said lever from twisting and 75 becoming disengaged from the rope. The lower end of the lever is connected by a link or bar 17 to the rear arm of a bell-crank lever 18, which is fulcrumed at its angle 19 in an upright guide 20. The upright guide, which 80 supports the lever 18, is mounted on the front portion of the chair above the foot-rest thereof, and the front arm of the bell-crank lever is provided with a lateral extension or foot-piece 21, which is arranged to be engaged by 85 the foot of a person. When the foot-piece is depressed, the bell-crank lever is oscillated and the upper arm of the actuating-lever is swung rearward into engagement with the rear suspension-rope, thereby actuating the 90 swing and producing a gentle easy motion of the same. The foot-piece of the bell-crank lever is arranged at one side of the chair, out of the way, and is not liable to catch the clothing or foot of a person using the swing. 95

What I claim is—

1. The combination with a chair, and means for suspending the same from a suitable support of an upright lever, fulcrumed between its ends on the chair at the back thereof, and engaging the said means and a foot-lever fulcrumed on the chair at the front portion thereof and connected with the upright lever, substantially as described.

2. The combination of a chair, provided at the back with a horizontal guide and having an upright guide at the front, means for suspending the chair from a suitable support,
5 an upright lever fulcrumed between its ends on the back of the chair, with its upper arm engaging the said means and its lower arm arranged in said horizontal guide, a bell-crank lever fulcrumed at its angle in the up-
10 right guide, and provided at one arm with a lateral extension forming a foot-piece, and a

link connecting the other arm of the bell-crank lever with the lower arm of the upright lever, substantially as described.

In testimony whereof I have hereto affixed my signature in the presence of two witnesses.

ALVAH A. HOFFMAN.
